H. C. NOE,
ELECTRIC LIGHT CLUSTER.
APPLICATION FILED MAY 20, 1920.

1,366,093.

Patented Jan. 18, 1921.

Inventor
Harold C. Noe
By his Attorney
Charles R. Searle.

UNITED STATES PATENT OFFICE.

HAROLD C. NOE, OF EAST ORANGE, NEW JERSEY.

ELECTRIC-LIGHT CLUSTER.

1,366,093.

Specification of Letters Patent. Patented Jan. 18, 1921.

Application filed May 20, 1920. Serial No. 382,833.

To all whom it may concern:

Be it known that I, HAROLD C. NOE, a citizen of the United States, residing at East Orange, in the county of Essex and State 5 of New Jersey, have invented a certain new and useful Improvement in Electric-Light Clusters, of which the following is a specification.

The invention relates to means for supporting electric lamp-sockets on a standard, usually in pairs or clusters extending radially from the standard and angularly thereto, and the object of the invention is to provide simple, easily operated means for 15 varying the angular positions of the sockets vertically as desired and for holding the sockets reliably in the adjusted positions against any strains tending to depress them, as for example, the strain of the switch-chain in lighting or extinguishing the lamps.

The invention consists in certain novel features of construction and arrangement by which the above objects are attained, to be hereinafter described and claimed.

25 The accompanying drawings form a part of this specification and show the invention as it has been carried out in practice, applied to a standard having a cluster of four lamps.

30 Figure 1 is an elevation showing the upper end of a standard thus equipped.

Fig. 2 is a corresponding vertical section, partly in elevation.

35 Fig. 3 is a plan view with a portion removed to show the arms to which the sockets are attached.

Fig. 4 is a perspective view of one of such arms.

Similar letters of reference indicate the 40 same parts in all the figures.

The standard comprises a vertical tube A adapted to contain the wires or conduits for the lamps, having a hemispherical cup B at the upper end, covered by a hemispherical cap C forming with the cup a spherical shell. A screw-threaded hollow nipple A¹ at the upper end of the tube extends through a central opening in the cup and receives a threaded collar D which clamps the cup firmly to the tube.

50 Above the collar D is a pedestal D¹ joined to the collar by arms D² forming with the collar an open frame within the shell. Into the pedestal D¹ is screwed a vertical screw-threaded stud F extending axially of the shell and projecting through a central hole

in the cap C. The protruding end receives a cap-nut E by which the cap C is held to the cup B. The latter is provided with vertical slits or deep notches b extending downwardly from its rim, and the cap C has a flange or skirt C¹ inclosing such rim.

G are lamp-sockets of any approved type, shown as equipped with pulls or switch-chains G¹, and adapted to receive the usual lamp bulbs, not shown. Each socket is screwed upon a nipple H¹ projecting radially through one of the slits b and mounted on the lower end of a curved arm H within the shell. Each arm H is provided with a longitudinally extending slot h receiving the stud F.

Four arms H are shown in the drawings arranged at an angle of 90° each to the other, with four sockets G extending radially from the cup B. The four arms lie one upon the other with the lowermost supported upon an abutment J, shown as a nut, on the stud F, and the uppermost supports the cap C. Thus arranged the act of screwing the cap-nut E upon the stud F forces down the cap C and compresses the arms H between latter and the abutment J, and by the frictional contact thus induced holds the arms firmly against longitudinal movement in the direction permitted by the engagement of the stud F in the slots h and the nipples H¹ in the slits b.

The arms are of thin metal and are curved on radii corresponding to the interior of the spherical shell formed by the cap and cup, so that when the pressure is lessened by relaxing the cap-nut E, the nipples H¹ and connected lamp-sockets may be moved up or down in the slits b to an extent determined by the length of the slits or length of the slots h inclosing the stud F.

Sufficient friction may be maintained to hold each socket in the desired angular position until all are adjusted, and a further tightening of the cap-nut binds all the arms frictionally and all the sockets are thus held firmly and reliably.

Any number of arms may be employed with a correspondingly slotted cup, by adjusting the threaded abutment J to the space occupied by the superposed arms H as will be understood.

The sockets G may be attached to the nipples H¹ while the arms H are removed from the cup B and the wiring easily accomplished with the parts thus exposed; the

arms H are then successively threaded upon the stud F through the slots h, with the nipples H¹ inserted in the open ends of the slits b, and moved downward therein. The cap 5 C is then applied and the cap-nut E screwed on the stud to induce a degree of friction sufficient to hold the arms temporarily while the sockets are adjusted to the desired vertical angle, and then tightened to hold the 10 arms securely in the adjusted positions.

The open frame formed by the collar D and its arms D² and pedestal D¹ permits the wires from the tube A to be conveniently manipulated in making the electric connections to the sockets G; and the open space in the shell, beneath the arms H, offers ample room for nesting any slack in the wires between the nipple A¹ and socket-nipples H¹ required in permitting the adjustment of the 20 sockets.

A lamp-shade M or similar accessory may be supported on the cap C and held by the cap-nut E, as indicated in dotted lines in Fig. 1:

25 I claim:

1. In a device of the character set forth, a cup having slits therein, a plurality of superimposed arms within said cup, having nipples extended outwardly through such 30 slits, movable in the latter and adjustable in the direction of the length thereof, adapted to carry lamp-sockets, and means for clamping said arms one upon the other to hold such sockets in position.

35 2. In a device of the character set forth, a cup having slits therein, a stud in said cup, a plurality of superimposed arms each having a slot inclosing said stud, and a nipple extended outwardly through one of such 40 slits, adapted to carry a lamp-socket, and means coacting with said stud for clamping said arms one upon the other to hold such sockets in position.

45 3. In a device of the character set forth, a hemispherical cup having slits therein, a plurality of superimposed curved arms within said cup, each having a nipple extended through one of such slits and adapted to carry a lamp-socket, and means for 50 compressing said arms into strong frictional contact with each other.

55 4. In a device of the character set forth, a hemispherical cup having slits therein, a hemispherical cap covering said cup and forming with the latter a spherical shell, a stud in such shell extending through said cap, a plurality of curved arms within such shell, each having a slot inclosing said stud, and a nipple extended outwardly through 60 one of such slits, adapted to carry a lamp-

socket, an abutment on said stud beneath said arms, and a nut on said stud exterior of said cap.

5. A hemispherical cup having slits therein, a hemispherical cap covering said cup and forming with the latter a spherical shell, an axially located stud in such shell extended through said cap, a plurality of superimposed curved arms within said shell, each having a slot inclosing said stud, and a nipple extended outwardly through one of such slits, adapted to carry a lamp-socket, an abutment on said stud beneath said arms, and means operable on the exterior of such shell and coacting with said stud and abutment for compressing said arms upon each other. 65 70 75

6. In a device of the character set forth, a cup having slits therein, a plurality of superimposed arms within said cup, each having a nipple extended outwardly through one of such slits, a stud in said cup extended through said arms, an abutment on said stud beneath said arms, and means above said arms, coacting with said stud and abutment for compressing said arms upon each other. 80 85

7. In a device of the character set forth, a hemispherical cup having a slit therein, an arm in said cup curved substantially concentrically to said cup, having at one end a longitudinal slot and at the other end a nipple extended outwardly through such slit and adapted to carry a lamp-socket, an abutment in said cup, and means extending through such slot for clamping said arm to said abutment. 90 95

8. In a device of the character set forth, a hemispherical cup having slits therein, a plurality of arms in said cup curved substantially concentrically to said cup and overlapping one upon another; each of said arms having a slot and a nipple extended outwardly through one of such slits and adapted to carry a lamp-socket, a stud in 100 said cup extending through such slots, an adjustable abutment on said stud beneath said arms, and a nut on said stud above said arms, adapted to compress said arms upon each other. 105 110

9. In a device of the character set forth, a cup having slits therein, a plurality of arms within said cup, having nipples extended outwardly through said slits, movable in the latter and adapted to carry lamp-sockets, and means for clamping said arms to hold such sockets in position. 115

In testimony that I claim the invention above set forth I affix my signature.

HAROLD C. NOE.
